UNITED STATES PATENT OFFICE.

GEORGE C. KERR, OF BRAINERD, MINNESOTA.

FUEL-SUPPLY-RECORDING DEVICE.

1,194,640.

Specification of Letters Patent. Patented Aug. 15, 1916.

Application filed March 24, 1915. Serial No. 16,664.

To all whom it may concern:

Be it known that I, GEORGE C. KERR, a citizen of the United States, residing at Brainerd, in the county of Crow Wing and State of Minnesota, have invented certain new and useful Improvements in Fuel-Supply-Recording Devices, of which the following is a specification.

My invention relates to fuel supply recording devices for boilers, and has for its object to provide in association with the door of a furnace for the boilers certain mechanism which will automatically record each time the door is opened and closed, will automatically record each shovelful of coal thrown into the furnace, will record each time the boiler blows off through the safety valve, and provides a recordable device for rendering it impossible for the fireman to throw coal into the furnace without properly distributing the same.

In carrying out my invention, I provide a record tape with instrumentalities for advancing and punching said tape in accordance with the operations above specified in combination with a clock which makes a record mark upon the tape at the expiration of each period for which the clock is set, such period being preferably long enough so that it would be impossible for the furnace to be neglected by the fireman over as great a period. The instrumentalities above referred to consist of record actuating mechanism which advances the tape each time the door is opened and punches the tape each time the door is closed, which punches and advances the tape each time a shovelful of coal is thrown into the furnace and which marks the tape each time the engine pops off and will continue to make such mark until the safety valve exhaust ceases.

In addition to the above devices a further and extremely important part of my invention is a door obstructor which is pneumatically caused to be moved across the door of the furnace after the same is opened so as to obstruct said door and prevent throwing another shovelful of coal into the furnace before the door is closed and again reopened. This obstructor, however, is not moved so rapidly but what the fireman can throw in a shovelful of coal after the door is opened, and if such shovelful of coal is thrown properly so that the shovel strikes

the bottom of the fire-door opening to scatter the coal as should be done, the moving means for the door obstructor will be released and the same momentarily withdrawn giving time to throw in another shovelful of coal. But this requires that the shovel shall strike the bottom of the fire-door opening which includes a device for effecting the record above referred to. The movement of the door obstructor also results in marking the tape and making a record thereon. It will be apparent from the above that, generally stated, the record tape resulting from these operations will show exactly the manner in which the furnace has been fired.

The applicability of the device, particularly to locomotives where the waste of coal from improper firing may be, and usually is, very great will be fully apparent, for with such a record the traveling engineer can check up on the fireman, and those who fail to comply with the regulations and practices of good firing can be called to task and if necessary dismissed. The use of the apparatus will, therefore, result in greatly improved work on the part of firemen and in large saving of coal consumption.

The full objects and advantages of my invention will appear in connection with the detailed description thereof and are particularly pointed out in the claims.

In the drawings, illustrating the application of my invention, in one form,—Figure 1 is a front elevation of a boiler such as a locomotive boiler head showing the fire door and openings connected therewith. Fig. 2 is a fragmentary view of a sliding type door associating with my improvements. Fig. 3 is a section through the door shown in Fig. 1 in closed position. Fig. 4 is a similar sectional view in open position. Figs. 5 and 6 are fragmentary sectional views showing the door latching mechanism and the means of operating the register upon opening and closing of the door. Figs. 7 and 8 are plan and sectional detailed views showing means for operating the register when the boiler pops off. Fig. 9 shows the means of locking the door in open position. Fig. 10 is a vertical sectional view of the control devices for the pneumatic mechanism for releasing the door and for projecting the door obstructor. Fig. 11 is a horizontal sectional view on line 11—11.

of Fig. 10. Fig. 12 is a plan view of the registering device with the cover raised and some parts broken away or in section. Fig. 13 is a transverse section through the length 5 of the register box. Fig. 14 is a transverse section across the width of said box. Fig. 15 is a detail view showing the clock control for the time recording mechanism. Figs. 16 and 17 are views showing the manner 10 of printing the tape. Fig. 18 is a sectional front elevational detail view of some of the parts shown in Fig. 1.

As illustrated in Fig. 1, the boiler head 20 is provided with a fire ring 21 surrounding 15 the opening 22 in the furnace or fire box and having a door 23 supported by extended lugs 24 hingedly connected at 25 with brackets 26 extended outwardly from the boiler head. The door 23 is provided with a latch 20 bar 27 centrally pivoted at 28 to the front of the door and restrained by a keeper 29, said latch bar engaging a latch arm 30 fast on the ring 21. A handle 32 on latch bar 27 is provided for the use of the operator. 25 The above is a common form door employed for locomotive boilers. Another form is shown in Fig. 2 in which two sliding members 33 and 34 are adapted to be moved along guide bars 35 and 36 being operated 30 by links 37 and 38 having slotted connections 39 with the sliding sections 33 and 34, said links being automatically operated by well known means not shown. The alternative form of door is shown in Fig. 2 as 35 my invention is equally applicable to either type of door and because both types of doors are in common use.

As indicated in Fig. 1, the latch bar 27 has a radial extension 40 provided with an 40 angularly disposed toe 41. When the door is swung open the toe 41 will engage an arm 42 rigidly connected with a rod 43 which, in turn, is fast to a piston 44 slidably mounted in a bore 45 in a casing 46 secured to the boiler head 20, said piston being forced into normal outward position by means of a coil spring 47 in the bore 45. The toe 41 also passes beneath a latch 48 on the bracket 26 and into a notch 49 50 in said latch. A swinging latch 50 is connected by means of links 51 with the latch bracket 48, and is also connected by means of a bent rod 52 with a piston 53 in a cylinder 54 secured to the boiler head 20, a 55 coil spring 55 normally acting to force said piston downward so as to hold the swinging latch 50 out of the path of toe 41, said latch being operated by means hereinafter described to force said latch 50 upwardly 60 when the door has been opened and hold the same locked open, as indicated in Fig. 9. As best indicated in Figs. 5 and 6, the opening and closing of the door operates indicating mechanism as will be later more fully explained. A piece 56 is fast on a rock shaft

57 journaled in brackets 58 and 59 secured to the boiler head 20. The piece has a curved finger 60 which extends into the path of the latch bar 27 and also is provided with a leaf spring 61 engaging the boiler 70 head 20. When the door is opened, the leaf spring will force the piece 56 and the engaging member 60 forwardly as shown in Fig. 5. When the door is closed, the latch bar will engage member 60 and rock the 75 piece 56 inwardly against the force of spring 61 into the position shown in Fig. 6. The rock shaft 57 has thereon an arm 62 to which is pivotally connected a plunger rod 63 running to a record box 64 and effecting, 80 in the manner hereinafter described, a recording operation every time the door is opened and closed.

In the proper firing of a boiler furnace, the fireman should strike the shovel containing the coal upon the bottom of the fire door opening thereby causing the coal to scatter and spread over the burning surface within the fire box. This is essential to obtain the best results from the coal delivered to the 90 furnace because if it is thrown in in bulk it will result in gas being set free above a comparatively cool mass of coal so that said gas will not be consumed and will pass from the furnace in the form of black 95 smoke, being wasteful of fuel. It is important, therefore, that I have provided means whereby a record will be made of each shovelful of coal delivered to the furnace in the proper manner wherein the 100 shovel is caused to strike the bottom of the fire door opening, and I have also provided means rendering it impossible to throw more than one shovelful of coal into the furnace without so striking the bottom of the 105 fire door opening. To effect the first of these results I provide, as shown in Fig. 1, a rod 65 slidably mounted at its lower end in a bracket 66 secured to the boiler head 20. The upper end of rod 65 has 110 connected therewith a plate 67 which projects through a slot in the bottom of the fire door ring 21, the slot and bracket 66 forming the means for guiding the plate 67 and rod 65 in vertical movements. A 115 spring 68 surrounding rod 65 between a collar 69 thereon and the bracket 66 forces plate 67 up through the slot so that the same is projected above the lower surface of the fire door ring as indicated in dotted 120 lines in Fig. 1. Pivoted to rod 65 at 79 is a lever 71 which in turn is pivotally connected intermediate its ends to a stand 72 on the boiler head 20, the other end of lever 71 being pivotally connected at 73 with a 125 plunger rod 74 which extends into the record box 64 alongside of plunger 63. Pivotally connected to rod 65 in the same plane as lever 71 is another lever 75 which is pivoted intermediate its ends at 76 to a 130

stand secured to boiler head 20, the other end of said rod being pivotally connected at 77 with a rod 78 upon the upper end of which is a cylindrical plunger 79 operative in a bore 80 extending through the casting 46 in a direction at right angles to and so as not to intersect the bore 45 in which piston 44 operates, the piston 70 being normally pushed into retracted position by a spring 81 in the bore 80 and another spring 82 engaging a piston 83 in a cylindrical casing 84 formed in connection with cylinder 54, piston 83 being connected by means of a bent rod 85 with rod 78, as best shown in Figs. 10 and 11.

It will be apparent from the above that when the fireman delivers a shovelful of coal properly to the furnace, he strikes the shovel upon the plate 67 which will depress that plate, thereby rocking lever 71 to effect a recording operation in record box 64 and simultaneously oscillating lever 75 to force upwardly piston 70 in bore 80 and piston 83 in cylinder 84.

An air cylinder 86 is secured upon the boiler head 20 at an angle such that when a door obstructor rod 87 is projected therefrom, it may at the end of its movement strike plate 67 and automatically operate the same. The rod 87 is secured to a piston 88 in the cylinder 86 and is normally held in retracted position by a spring 89 within said cylinder. Compressed air from the storage tank of the engine may be admitted into cylinder 86 above piston 88 through a pipe 90 which, as clearly shown in Fig. 10, is adapted to be placed in connection with the supply pipe 91 by fixed passageways 92, 93, and 94 in casting 46 and a movable passageway 95 in piston 44 and another movable passageway 96 in movable piston 70, the passageway 93 connecting the bores 45 and 80 while the passageway 94 opens into the bore 80 and the passageway 92 opens into the bore 45. All of said openings are in alignment so that when the passageways 95 and 96 in pistons 55 and 70, respectively, are brought into alignment an unobstructed air passageway extending from supply pipe 91 to delivery pipe 90 and cylinder 86 is provided. The normal position of piston 70 under the influence of springs 81 and 82, as shown in Fig. 10, brings passageway 96 into connection with passageways 94 and 95, the normal position of piston 44 places the passageway 95 therein out of alignment with passageways 92 and 93, thereby operating to shut off flow of air. When the door is thrown open, however, as indicated in Figs. 10 and 11, the toe 41 engaging piece 42 pushes piston 44 upwardly so as to bring passageway 95 into alignment with passageways 93 and 94, thereby permitting flow of air to delivery pipe 90 which immediately actuates piston 88 and starts to move ob-

stricter member 87 across the opening of the fire door. As this obstricter is moved against the force of spring 89 some time will elapse after the beginning of its movements before it obstructs the fire box opening so much as to prevent the proper introduction of a shovelful of coal. This time is sufficiently ample to permit the fireman to gather and deliver a shovelful of coal after the door is opened. If this is done properly, the shovel will be struck upon the plate 67 which will be depressed and will, through lever 75 and rod 78, force piston 70 upwardly, thereby putting passageway 96 out of alignment with passageways 93 and 94 and cutting off the supply of air. At the same time, a passageway 97 in piston 70 is brought into alignment with a passageway 99 through casting 46 in communication with delivery pipe 90 and another passageway 100 in said casing which opens to atmosphere. This releases the air from back of piston 88 which, together with the obstricter, is immediately restored to initial position.

Upon the boiler head 20 adjacent cylinder 86 is a small cylinder 101 connected by pipe 102 with cylinder 86 below the normal position of piston 88, so that when compressed air is admitted to cylinder 86 above piston 88 through pipe 90, and the piston 88 is moved in the cylinder, air will be admitted through pipe 102 to cylinder 101. A piston 103 in cylinder 101 has the rod 104 thereof connected with a lever 105 pivoted adjacent its center to a stand 106 secured to boiler head 20. The other end of lever 105 is pivotally connected with a plunger rod 107 which goes to the record box 104, thus making a record every time the piston 88 and obstricter 87 connected therewith have been actuated and restored to position.

The operation of the member 50 for locking the door in open position is effected at the same time as actuation of the obstricter through compressed air delivered from pipe 91. As best shown in Fig. 10, this is accomplished by means of a pipe connection 108 which admits air through a check valve 109 and port 110 to cylinder 54 below piston 53. This drives the piston 53 upwardly and through the bent rod connections 52 rocks the latch 50 to the locking position shown in Fig. 9. A port 111 opens from cylinder 54 into cylinder 84 and is normally kept closed by the piston 83 in the last named cylinder. The operation of these devices will be apparent. When the door 23 is thrown open the toe 41 engages the bar 42 and brings port 95 into position to open communication from compressed air pipe 91 to pipe 90 and cylinder 86 above piston 88 and also through pipe 108 to cylinder 54 below piston 53. This has the effect of immediately beginning the movement of ob-

stricter 87 and at the same time forcing piston 53 up so as to swing latch 50 into position to lock the door open. The fireman cannot close the door without unlocking this device and this can only be effected by properly throwing a shovelful of coal into the furnace so that the shovel strikes the plate 67, as it should for scattering the coal. The fireman has time to do this before the ob-
5 stracter 87 gets in front of the door, if he operates with proper expedition. If, how-
10 ever, he delays or throws the coal in without striking the plate 67, the obstricter will be moved across the furnace door and it will
15 be impossible for the fireman to throw another shovelful of coal in until he has manually operated the plate 67 and parts connected therewith, thus necessitating the making of a record against himself when no
20 coal has been delivered to the furnace.

When the shovel strikes the plate 67, it not only results in the making of a record, as will hereinafter be pointed out, but it forces upwardly the rod 78 and with it pis-
25 tons 70 and 83, movement of the former re-
sulting first in breaking the connection from pipe 91 to pipes 90 and 108 and then opening to atmosphere pipes 99 and 100 through passageway 97, thus releasing the pressure
30 in cylinder 86 and permitting door obstruc-
ter 87 to be restored to initial position by spring 89. Meantime, piston 83 has first un-
covered port 111 and then has traveled past a port 112 open to the atmosphere which per-
35 mits air to exhaust from cylinder 54, when the spring 55 will force piston 53 downward rocking the latch 50 and unlocking the door. The door can then be closed. If, however, this is not immediately done, the springs 81
40 and 82 will restore pistons 70 and 83 to ini-
tial position reestablishing communication from compressed air pipe 91 to pipes 90 and 108 and again locking the door and pro-
jecting door obstricter 87, when it would be
45 necessary for the fireman to throw in another shovelful of coal or make a record to that effect in order to close the door. It is to be noted also that it will be impossible to close the door when the obstricter 87 is in
50 front of the same as the door is locked at all times that the obstricter is projected. Immediately upon closing the door, the toe 41 comes away from piece 42 and releases the piston 44 so that spring 47 can return the
55 same to initial position in which communica-
tion from compressed air pipe 91 is cut off. A notch 113 in the side of piston 94 is so po-
sitioned that when said piston is in normal inoperative position the notch will span the
60 opening from pipe 92 and a duct 114 leading to atmosphere, thereby permitting release of any air that may have been trapped in pipe 90 and cylinder 86.

The sliding doors illustrated in Fig. 2 op-
65 erate the above indicated instrumentalities

in the same manner, the difference being merely in the arrangement of the actuating parts. As shown, a lever pivoted at 116 is pivotally connected at 117 to plunger 63 and has a toe 118 which is caused to engage 70 a piece 119 on sliding door 34 by leaf spring 120, by which means the record of opening and closing the door is effected. The door 33 directly engages a piece 121 corresponding to the arm 42 by which piston 44 is ac-
75 tuated and a latch 122 is connected with rod 52 and engages in a notch 123 in door 33 for locking the same in opened position.

Within the record box 64 are journaled ribbon drums 124, 125 between which ex-
80 tends a recording ribbon 126. Upon cross partitions 127, 128 in the record box is a table 129 over which the ribbon or tape 126 is fed and above the table 129 is a plate 130 provided with a plurality of nipples 131. Holes 132 are provided in the table 129 and punch rods 133, 134, 135, 136, and 137 ex-
85 tend through apertures in the nipples 131 and are adapted to coöperate with the holes 132 to punch records in the tape 126. The punch rods are spring held out of engagement with the tape, as clearly shown. Rod 137 is operated by a finger piece 138 and is adapted to make a mark such as indicated at 139 in Figs. 16 and 17 upon the tape 126
90 showing the point on the tape where any particular engine crew takes over the engine. That is, in locomotive practice, the mark 139 would indicate the time of coming out of the round house. Punch 136 is pivotally connected with a lever 140 which is pivoted on a shaft 141 mounted on the cross pieces 127, 128. The lever 140 is pivotally connected at 142 with a lifter rod 143 slidable in a bearing in a shelf 144 and having its lower 100 end positioned in a socket 145, said socket being formed with a sloping rear wall 146. A spring 147 normally pushes rod 143 into position such that a sloping toe 148 may be engaged by a dog 149 on the plunger rod 74
105 which is actuated by the engagement of the shovel upon piece 67. The actuation of the plunger rod will lift the rod 143 and oscillate lever 140 sufficiently to cause punch bar 136 to punch the tape when the sloping toe 148
110 may slide off the dog 149 permitting the lever 140 and rod 143 to return to normal po-
sition and the punch bar 136 to be with-
drawn out of the tape 126. The rod 74 has thereon a pair of collars 150 which embrace 120 the forked end of a lever 151 loosely mount-
ed upon a shaft 152 which is journaled to ro-
tate in bearings in cross pieces 127, 128. Fast with lever 151 is an arm 153 having thereon a pawl 154 which engages the teeth 125 of a ratchet wheel 155 fast on shaft 152.

It will be apparent from an inspection of Fig. 14 that when the plunger 74 is actuated upwardly by the proper throwing in of a shovelful of coal, it will rock the pawl arm 130

153 backwardly permitting the pawl 154 to engage a new tooth of ratchet wheel 155 and upon removal of the shovel a spring 156 surrounding plunger rod 74 will restore the 5 parts to initial position and, in doing so, will rotate ratchet wheel 155. As this wheel is fast on shaft 152 it will rotate a bevel gear 157 fast on shaft 152 which, through bevel gear 158 fast in the spindle for roller 10 125, will operate to forward the record tape 126 the proper distance. Punch rod 135 is connected to a lever 159 journaled upon rod 141 and is similar to and operated from plunger 63 in the same manner as lever 140. 15 The lever 63 actuates a lever 160 loosely mounted on shaft 152 having an arm 161 carrying a pawl 162 which engages ratchet wheel 155. The plunger rod 63, it will be borne in mind, is actuated by the opening 20 and closing of the door 23 (or 33, 34), closing of the door operating to lift the rod and effect punching of the tape at the same time positioning pawl carrying arm 161 while opening of the door will, through operation 25 of spring 61 and a spring 163 surrounding rod 63 restore the parts thereof rocking the pawl arm 161 and through the ratchet wheel 155 and connections therefrom forwarding the tape. It is thus apparent that after each 30 shovel of coal deposited in the furnace and after each opening of the door the tape will be forwarded a distance of one notch. The punch marks for these respective records may be different in character, the shovel 35 marks being as indicated at 164 in Figs. 16 and 17, while the door closing marks will be as indicated at 165. The aggregate number of shovels of coal going into the furnace may readily be recorded by a numbering machine 40 indicated diagrammatically at 166 and operated by a lever 167 connected with spindle 74 as shown in Fig. 1.

The push rod 107 operated by compressed air from cylinder 103 to show the number of 45 actuations of obstructor 87 actuates a lever 168 pivoted to rod 141 in a similar manner to that shown in detail for the operation of lever 140 by push rod 74, a lever 168 operates punch bar 134 to make record punches 50 indicated at 169 in Figs. 16 and 17. No forwarding of the tape is effected in making this record which will appear either below or substantially below the shovel marks 164.

As above pointed out the tape 126 is forwarded entirely by the opening of the door and the throwing in of shovelfuls of coal. The forwarding of the tape will not be entirely regular as to rate; but it is desirable to mark upon the tape successively indications which, upon inspection, will show that a given period of time has elapsed between any two succeeding marks, from which it follows that the period of time covered by any length of tape would be a time equal 60 to the selected period multiplied by the

number of marks appearing on the tape. In order that the time marks, which are effected by a clock, shall not fall upon one another, it is necessary that the period of time shall be so great that the fire will require attention during that period. A suitable period therefor is fifteen minutes. The printing of time marks is effected by a clock 170 secured in the record box as shown in Figs. 12, 13, and 15. For indicating the 70 quarter hour periods, the clock is provided with a cam head 171 on the stem which normally operates the hour hand, said cam head having a series of four cam extensions 172 with radial drops. A lever 173 preferably 75 provided with a weight 174 has a head 175 which engages said cam extensions 172, said lever being pivoted to a stand 176. The lever 173 engages a collar 177 on a rod 178, said rod being pivotally connected with a 80 lever 179 journaled upon rod 141. Connected to the lever 179 in front of its point of pivotal connection with rod 141 and by means of a flexible connector 180 is a short arm 181 having a weighted head 182 to 85 which is pivoted the punch rod 133. The operation of this device is very plain. The lever 173 is rocked by a cam projection 172 on the cam head 171 which is rotated by the clock. By this means the plunger 178 90 is depressed against the force of spring 183 surrounding said plunger. When the operation of the clock finally takes the cam extension from under the head 175 of lever 173 the spring 183 forces the parts upwardly quickly rocking lever 179 and throwing arm 181 and weighted head 182 downwardly with sufficient force to drive the punch rod 133 through the paper tape 125, said head rebounding to take the rod out of 95 the tape. Time marks which may not be more than a small needle punch are indicated at 185 in Figs. 16 and 17.

It is undesirable to fire a locomotive so as to produce more steam than can be used, resulting in what is known as popping of the safety valve, thus resulting in waste of fuel. To keep a record of the number of instances of such popping and the duration of each 100 relatively, I provide a lever 186 journaled 105 upon a bracket 187 formed on cross partition 128. Upon an arm of said bracket is mounted a pointed spur wheel 188 which is adapted to extend through a slot 189 in the table 129 and engage the tape 126, being 110 normally held out of engagement with said tape by a spring 190. Said spur wheel 188 also may extend into a slot 191 in plate 130 so that when brought into engagement with the tape, the spur wheel will make a perforate line which will be extended through movement of the tape as long as the spur wheel is held in engaging position, as indicated at 192 in Fig. 16. To the lever 186 is 115 attached a rod 193 which extends through 120 125 120 125 130

the record casing 64 and a pipe 194 to a rocking lever 195 at the junction of said pipe. The pipe is extended through sections 196 and 197 to a point in proximity to the 5 safety valve 198 and through this pipe extends a flexible connector 199 which is fastened to a plate 200 pivoted at 201 and projection 202 from pipe 197, as best shown in Figs. 7 and 8. The plate 200 has a wing 10 203 which overlies a portion of the steam escape port 204, being normally held upon the same by means of a spring 205. When the engine pops, the force of the escaping steam impinging upon the wing 203 will lift 15 said wing and through connections 199, 193 will rock lever 186 against the force of spring 190 so as to project spur wheel 188 through slot 189 and into contact with tape 126 where it will remain until the pressure 20 in the boiler falls sufficiently to permit the safety valve to cut off. If during the period the door of the furnace is opened or coal is thrown into the furnace the tape will be forwarded and the mark indicating the duration 25 of the escape of steam through the safety valve will be correspondingly extended.

The operation of my device has been very fully given in connection with the detailed 80 description thereof. It is apparent that by its use a complete record will be made of the character of service rendered by the fireman in firing the engine (whether locomotive or stationary). This record will show 85 the manner of delivering the coal from the shovel to the furnace, will necessarily show each shovelful delivered, the total number full of shovelfuls; will show the number of shovelfuls for any fifteen minute period or 90 correspondingly for any period which is a multiple of fifteen minutes; will show whether or not one shovel has been introduced into the furnace at each time that the door has been opened and closed; will show 95 45 how often the steam has been raised in the boiler so that the engine pops off, and, in general, will show exactly the kind of work the fireman is doing and will enable the road engineer or superintendent in charge of such 100 50 operatives to correct deficient operation, to select the men in accordance with the effectiveness of the work which they are doing, will reduce waste of fuel, and will operate as an incentive to the fireman since it 105 55 makes it possible for the conscientious and efficient man to have the character of his work known.

I claim:

1. In combination with the door of a furnace, a fuel supply recorder comprising a tape, and means within the door opening when the door is opened adapted to be actuated by the shovel when the fireman throws in a shovelful of coal for making a record 60 upon the tape.

2. In combination with the door of a furnace, a fuel supply recorder comprising a tape, means within the door opening when the door is opened adapted to be actuated by the shovel when the fireman throws in a shovelful of coal for making a record upon the tape, and means for forwarding the tape after each actuation. 70

3. In combination with the door of a furnace, a fuel supply recorder comprising a 75 tape, and means for effecting a record upon said tape and for forwarding the tape each time the door is opened and closed.

4. In combination with the door of a furnace, a fuel supply recorder comprising a 80 tape, means for forwarding the tape rendered operative by opening of the door, and means for making a record on the tape when the door is closed.

5. In combination with the door of a furnace, a fuel supply recorder comprising a tape, means for punching the tape including a sliding rod having a bevel faced projection thereon, said rod being mounted for side swinging movement when the same has 90 been slid longitudinally a sufficient distance to effect the punching operation, a plunger having a pivoted toe for engaging said projection to slide the rod until the same becomes displaced laterally to permit passage 95 of the plunger and to return to position upon the return of the plunger, and means engaged by the door when the same is closed for operating the plunger.

6. In combination with the door of a furnace, a fuel supply recorder comprising a 100 tape, means for punching the tape, means including a ratchet for forwarding the tape, a plunger, a swinging arm having operative connection with the plunger and provided with a pawl for operating the ratchet when the arm is moved by return movement of the plunger said plunger being adapted to operate the punching means when the same is moved outwardly, means 105 engaged by the door when the same is closed for moving the plunger outwardly, and a spring for returning the plunger when the door is opened.

7. In combination with a boiler and the 115 furnace door thereof, a fuel supply recorder comprising a tape, means actuated by opening and closing of the door for making a record upon said tape each time the door is opened and closed, and means adapted to 120 be actuated by the shovel when the fireman throws in a shovelful of coal for making a record upon the tape.

8. In combination with a boiler and the furnace door thereof, a fuel supply recorder 125 comprising a tape, means actuated by opening and closing of the door for making a record upon said tape each time the door is opened and closed, means adapted to be actuated by the shovel when the fireman 130

- throws in a shovelful of coal for making a record upon the tape, and means actuated by the escape of steam from the safety valve when the boiler blows off for making a record upon the tape.
9. In combination with a boiler and the furnace door thereof, a fuel supply recorder comprising a tape, means actuated by opening and closing of the door for making a record upon said tape each time the door is opened and closed, means adapted to be actuated by the shovel when the fireman throws in a shovelful of coal for making a record upon the tape, means actuated by the escape of steam from the safety valve when the boiler blows off for making a record upon the tape, a door obstracter, means for moving the door obstracter across the door opening when the door is opened, and means actuated by said moving means for making a record upon the tape each time the obstracter is actuated.
10. In combination with the door of a furnace, a fuel supply recorder comprising a tape, a door obstracter, means set in operation by opening of the door for operating said door obstracter, and means actuated by said obstracter operating means for making a record upon the tape each time the door obstracter is operated.
11. In combination with the door of a furnace, a door obstracter, means set in operation by opening of the door for operating said door obstracter, and means adapted to be actuated by the shovel when the fireman throws in a shovelful of coal for releasing the door obstracter and permitting the same to return to normal position.
12. In combination with the door of a furnace, a lock for holding the door open, a door obstracter, means set in operation by opening of the door for operating said door obstracter and for closing said lock, and means adapted to be actuated by the shovel when the fireman throws in a shovelful of coal for releasing said lock and said door obstracter to permit the door to be closed and the obstracter to be returned to normal position.
13. In combination with the door of a furnace, a cylinder having a piston therein, a door-obstructing arm adapted to be projected by air pressure within the cylinder, a source of supply for compressed air and a normally closed passageway therefor to said cylinder, and means actuated by opening of the door for opening said passageway.
14. In combination with the door of a furnace, a cylinder having a piston therein, a door-obstructing arm adapted to be projected by air pressure within the cylinder, air pipes in communication with said cylinder and a source of supply for compressed air, a member normally interrupting communication through said pipes, and means actuated by opening the door for positioning said member to complete communication.
15. In combination with the door of a furnace, a cylinder having a piston therein, a door-obstructing arm adapted to be projected by air pressure within the cylinder, air pipes in communication with said cylinder and a source of supply for compressed air, a piston movable across openings for said pipes and having a passageway therethrough adapted to register with the said openings, means for holding said piston normally so as to close the pipe, an arm connected with said piston, and a member on the door adapted to engage said arm when the door is opened and to move said piston and bring said passageway into registering position.
16. In combination with the door of a furnace, a cylinder having a piston therein, a door-obstructing arm adapted to be projected by air pressure within the cylinder, a spring for restoring the arm to initial position, a source of supply of compressed air and a normally-closed passageway therefor to said cylinder, means actuated by opening of the door for opening said passageway, and other means actuated by the shovel when the fireman throws in a shovelful of coal for again closing said passageway to permit the spring to restore the arm to initial position.
17. In combination with the door of a furnace, a cylinder having a piston therein, a door-obstructing arm adapted to be projected by air pressure within the cylinder, a spring for restoring the arm to initial position, a source of supply of compressed air and means forming a passageway therefor to said cylinder including an apertured block and a pair of apertured slides therein each adapted to open or close said passageway, one of said slides being normally in position to open and the other in position to close the passageway, means actuated by opening of the door for moving the normally-closing slide into opening position, and means actuated by the shovel when the fireman throws in a shovelful of coal for moving the normally-opening slide into closing position to permit the spring to restore the arm to initial position.
18. In combination with the door of a furnace, a cylinder having a piston therein, a door-obstructing arm adapted to be projected by air pressure within the cylinder, a spring for restoring the arm to initial position, a source of supply of compressed air and a normally-closed passageway therefor to said cylinder, means actuated by opening of the door for opening said passageway, and a member adapted to be engaged by said arm when the same is projected to its maximum obstructing position having connections

for again closing said passageway to permit the spring to restore the arm to initial position.

19. In combination with the door of a furnace, a cylinder having a piston therein, a door-obstructing arm adapted to be projected by air pressure within the cylinder, a spring for restoring the arm to initial position, a source of supply of compressed air and a normally-closed passageway therefor to said cylinder, means actuated by opening of the door for opening said passageway, and other means adapted to be actuated by said arm at its maximum projection or by the shovel when the fireman throws in a shovelful of coal for again closing said passageway to permit the spring to restore the arm to initial position.

20. In combination with the door of a furnace, a cylinder having a piston therein, a door-obstructing arm adapted to be projected by air pressure within the cylinder, a spring for restoring the arm to initial position, a source of supply of compressed air and a normally-closed passageway therefor to said cylinder, means actuated by opening of the door for opening said passageway, other means adapted to be actuated by said arm at its maximum projection or by the shovel when the fireman throws in a shovelful of coal for again closing said passageway to permit the spring to restore the arm to initial position, a recorder comprising a tape, means actuated by opening and closing of the door for punching the tape, means actuated by the compressed air as the same moves the arm for punching the tape, and means actuated by the projected arm or the shovel for punching the tape.

21. In combination with the door of a furnace, a fuel supply recorder comprising a tape, a door obstracter, means set in operation by opening of the door for operating said door obstracter, means adapted to be actuated by the shovel when the fireman throws in a shovelful of coal for releasing the door obstracter and permitting the same to return to normal position, and means simultaneously actuated to punch the tape.
22. In combination with the door of a furnace, a fuel supply recorder comprising a tape, a door obstracter, means actuated by opening the door for operating the door obstracter, means for terminating operation of the door obstracter and to restore the same to initial position, means for punching the tape, a block slidably mounted in the fire-door ring in position to be engaged by the shovel when the fireman drops the same upon the bottom of said ring in scattering the coal to the furnace, and levers connected with the said block for simultaneously operating said terminating means and said punching means.

23. In combination with the door of a fur-

nace, a fuel supply recorder comprising a tape, a clock and means operated by the clock for marking the tape at regular intervals of time, means within the door opening when the door is opened adapted to be actuated by the shovel when the fireman throws in a shovelful of coal for making a record upon the tape, and means for forwarding the tape after each said actuation.

24. In combination with the door of a furnace, a fuel supply recorder comprising a tape, a clock and means operated by the clock for marking the tape at regular intervals of time, and means for effecting a record upon said tape and for forwarding the tape each time the door is opened and closed.

25. In combination with the door of a furnace, a fuel supply recorder comprising a tape, a clock and means operated by the clock for marking the tape at regular intervals of time, means for effecting a record upon said tape and for forwarding the tape each time the door is opened and closed, means within the door opening when the door is opened adapted to be actuated by the shovel when the fireman throws in a shovelful of coal for making a record upon the tape, and means for forwarding the tape after each actuation.

26. In combination with the door of a furnace, a cylinder having a piston therein, a swinging lock for holding the door open adapted to be moved into locking position by air pressure within the cylinder, air pipes in communication with said cylinder and a source of supply for compressed air, a member normally interrupting communication through said pipes, and means actuated by opening of the door for positioning said member to complete communication.

27. In combination with the door of a furnace, a cylinder having a piston therein, a swinging lock for holding the door open adapted to be moved into locking position by air pressure within the cylinder, air pipes in communication with said cylinder and a source of supply for compressed air, a member normally interrupting communication through said pipes, means actuated by opening of the door for positioning said member to complete communication, and means adapted to be actuated by the shovel when the fireman throws in a shovelful of coal for rebreaking communication to permit the door to be closed.

28. In combination with the door of a furnace, a swinging lock, a door obstracter, means including a cylinder for operating the swinging lock by compressed air, means including a cylinder for operating the door obstracter by compressed air, a source of supply for compressed air and a normally-closed passageway therefor leading to both of said cylinders, and means actuated by

- opening of the door for opening said passageway and admitting compressed air to both cylinders and simultaneously operating the locking device and the door ob-
5 stracter.
29. In combination with the door of a fur-
nace, a swinging lock, a door obstracter
means including a cylinder for operating
the swinging lock by compressed air, means
10 including a cylinder for operating the door
obstracter by compressed air, a source of
supply for compressed air and a normally-
closed passageway therefor leading to both
of said cylinders, means actuated by open-
15 ing of the door for opening said passage-
way and admitting compressed air to both
cylinders and simultaneously operating the
locking device and the door obstracter, and
means adapted to be actuated by the shovel
- when the fireman throws in a shovelful of 2
coal for again closing said passageway to
permit release of the lock and the obstracter
to be returned to normal position.
30. A fuel-supply recorder comprising a
recording tape, means within the door open- 25
ing when the door is opened adapted to be
actuated by the shovel when the fireman
throws in a shovelful of coal for making a
record upon the tape, and a numbering ma-
chine actuated by the same means for keep- 30
ing a record of the aggregate number of
shovels of coal going into the furnace.

In testimony whereof I affix my signature
in presence of two witnesses.

GEORGE C. KERR.
